TIE RACK

William Kratt, Elizabeth, N. J.

Application March 31, 1934, Serial No. 718,321

1 Claim. (Cl. 211—124)

The present invention relates to racks for ties or like articles and has for its main object the provision of a comparatively simple and inexpensive device whereby ties or the like can be conveniently suspended from a wall and securely held in position.

With this object in view, my invention consists in the novel construction, arrangement and combination of parts which will be hereinafter more fully described and defined in the appended claim.

In the accompanying drawing in which similar reference characters denote corresponding parts,

Fig. 1 is a sectional elevation of my device, showing the same both in clamping and unclamping positions;

Fig. 2 is a front elevation thereof;

Fig. 3 is a perspective view thereof;

Fig. 4 is a side elevation, partly in section, of a modified construction of my device;

Fig. 5 is a front elevation thereof; and

Fig. 6 is a modified detail of my device.

Referring first to the construction shown in Figs. 1, 2 and 3, my device comprises a bracket or base plate 10 provided on top and at the bottom with eyelets 10' or the like, for the passage of screws 11 whereby said bracket may be fastened to a wall W, the inner face of a closet door, or the like.

30 Fixed to an upper part of the bracket or plate 10 as at 12' is a resilient member in form of a plate spring 12 which extends longitudinally of the bracket and whose free end projects somewhat below the bottom edge of the latter. Fixed 35 to said free end is a sleeve 13, loop or the like, in which is borne a rod 14 or bar, to extend at a right angle to the bracket 10 and which serves as a hanger or rack proper for ties, or like articles, as shown in Fig. 3. Said resilient member

40 12 has a tendency to draw the rod 14 normally toward the wall W so that the articles folded around the rod will be clamped between the latter and the wall and thus securely held in position. In order to permit the convenient hanging 45 of the articles over said rod and their removal therefrom I provide an arm 15 extending longitudinally of the bracket and having an aperture 15'. This arm at its lower end is pivotally joined to the lower end of the bracket 12 as at

50 15' to swing vertically and at its upper end is slightly curved forwards to form a grasp or handle 15³. The plate spring 12 extends through said aperture 15' of said arm 15, the lower edge 55 15⁴ of which aperture is a certain distance away from the pivotal axis of said arm so that when the latter is swung downwardly on its pivots 15², as shown in Fig. 1, said edge 15⁴ will engage the plate 12 and against the tension of the spring

force of said plate 12 push it away from the bracket 10. As a result thereof the rod carrying the articles will be swung away from the wall clearing the space between itself and said wall and permitting the hanging of the articles around or removal thereof from said rod. When the arm 15 is swung upwardly into the position shown in Fig. 3 the plate 12 is released and will be drawn back into clamping position shown by dotted lines in Fig. 1.

10 Instead of clamping the articles between the wall and the rod, I may provide an auxiliary rod to cooperate with the hanger rod as shown in the modification of Figs. 4 and 5. Here the bracket or plate 10^a is formed at its lower end to a loop 15 or sleeve 16 which bears an auxiliary rod 17 against which the rod 14 borne in the loop or sleeve 13 of the spring 12 is adapted to be drawn to clamp between themselves the ties or the other articles hung on the rod 14.

20 The apertured bar or plate 15 actuates the spring 12 in the same manner as in the first described construction.

The rods 14 and 17 may be circular in cross-section as shown in Figs. 1 to 5, square or of 25 other suitable configuration.

In Fig. 6 the rod 14^a is shown provided longitudinally with a number of protuberances 18, ribs or the like to form partitions for separating adjacent ties and the ends 14^b of said rod 14^a 30 may be bent upwardly as shown in Fig. 6, flanged or otherwise shaped to form stops which will prevent the ties from slipping off the rod.

35 Since various modifications may be made in the construction of the device without departing from the spirit of my invention, I do not wish to limit myself to the details shown and described.

What I claim is:

A rack or hanger for articles such as ties, comprising a bracket to be fixed to a wall or the like, a plate spring extending longitudinally of the bracket and whose free end projects below the bottom edge of the latter and is formed with a sleeve, a rod borne in said sleeve to extend at a right angle to said bracket and adapted to serve as the hanger proper, said plate spring having the tendency to swing toward said wall and in cooperation with the latter to clamp said articles in position thereagainst, a longitudinally apertured arm pivoted to said bracket to swing vertically, said plate spring being adapted to pass through the aperture of said arm, the lower edge of said aperture being a certain distance away from the axis of said arm so that when the latter is lowered said edge will engage said plate spring and swing it into and retain it in disengaging position.

WILLIAM KRATT.
